UNITED STATES PATENT OFFICE.

JAMES B. SMITH, OF LOS ANGELES, CALIFORNIA.

METALLIC SECTIONAL BARREL.

No. 902,846.

Specification of Letters Patent.

Patented Nov. 3, 1908.

Application filed January 28, 1907. Serial No. 354,421.

To all whom it may concern:

Be it known that I, JAMES B. SMITH, a citizen of the United States, residing at Los Angeles, in the county of Los Angeles and 5 State of California, have invented new and useful Improvements in Metallic Sectional Barrels, of which the following is a specification.

My invention relates more particularly to 10 that class of barrels which are adapted to hold solid or semi-solid substances, such as sugar, potatoes, tar, putty and the like; and it is the prime object of my invention to produce a metallic barrel which will particularly be adapted to hold these classes of 15 goods.

A further object is to provide a barrel which is stiff laterally.

A further object is to provide a barrel 20 which is collapsible and easily assembled.

A further object is to provide a barrel which is indestructible by all ordinary usage.

A further object is to provide a barrel which is simple and cheap in construction.

25 I accomplish these objects by means of the device herein described and shown in the accompanying drawings, in which:—

Figure 1 is a perspective view of my improved barrel. Fig. 2 is a detail sectional 30 perspective of the lower end of the barrel. Fig. 3 is a detail perspective of the joint used to connect the sections.

Referring to the drawings the barrel is made up primarily of a plurality of segments, three in this case, 1, 2 and 3, and a head 4. The segments each have an angle-iron 5 riveted to their tops, which serves as a lateral stiffener for the barrel besides finishing off the top. Riveted to one of the 40 longitudinal edges of each segment are cover plates 6, on the inside, and 7 on the outside. These cover plates project beyond the edges of the segment plates, as shown in Fig. 3 so that the edge of the adjoining segment plate 45 may be inserted between the projecting ends. At the bottom end of the segments are riveted angle-irons 8 and 9 with a space between them so as to provide a space for the bottom head of the barrel. These angles, as 50 seen in Fig. 3, project beyond the longitudinal edges of the segment plates and bear against the adjacent segment plate, thereby stiffening the joint between the two plates materially. Inside cover plate 6 extends 55 from the top of angle-iron 8 to the bottom of angle-iron 5. Outside cover plate 7 ex-

tends the whole length of the barrel. Hoops 10 are provided to hold the segments together when the barrel has been assembled and are slipped on without any fastening. 60

In the assembling of my barrel, the bottom head is first placed in the groove between the bottom angles of one of the segments. A second segment is then put in place by slipping its longitudinal edge into 65 the space between the cover plates on the first segment, and keeping the head between the bottom angle-irons. The third segment is then placed in a manner similar to that in which the second was placed with the 70 exception that it must be joined with the free edge of the first segment at the same time. The hoops are then placed in position and forced down over the barrel so as to draw the segments tightly together. 75

In the foregoing manner I have constructed a barrel which is tight enough for all solid and semi-solid substances, and which is cheap and simple to construct and practically indestructible in use. When disassembled it lends itself to easy and cheap 80 transportation, the segments being laid inside of each other making a flat package.

Having described my invention, what I 85 claim is:—

1. In a sectional barrel, a plurality of side segments, double cover plates secured to one of the vertical edges of each of said segments and adapted to receive between them the free edge of the adjacent segment, 90 a head for the barrel, and angle irons secured to the lower ends of said segments adapted to receive said head between them, said angle irons over-lapping the adjacent segments, and means to bind said segments 95 together.

2. In a sectional barrel, a plurality of side segments, means to secure said side segments together, a head for the barrel, and angle irons secured to the bottoms of said segments adapted to receive the head between them, said angle irons over-lapping the adjacent segments. 100

3. In a sectional barrel, a plurality of side segments, means to secure said segments together, and angle irons secured to said segments, said angle irons over-lapping the adjacent segments. 105

4. In a sectional barrel, a plurality of side segments, double cover plates secured to one of the vertical edges of each of said segments and adapted to receive between them 110

the free edge of the adjacent segment, hoops for the barrel, a head for the barrel, and angle irons secured to the lower ends of said segments and adapted to receive said head between them, said angle irons over-lapping the adjacent segments.

In witness that I claim the foregoing I

have hereunto subscribed my name this 19th day of January, 1907.

JAMES B. SMITH.
